(57) **CLAIM**

The ornamental design for an elliptical cufflink, as shown and described.

DESCRIPTION

FIG. 1 is a perspective view of my design for an elliptical cufflink according to the invention;

FIG. 2 shows a side view thereof, with the opposite side view being identical;

FIG. 3 shows a front view thereof, with the rear view being identical;

FIG. 4 shows a bottom view thereof, with the top view being identical;

FIG. 5 shows a perspective view of an alternate embodiment of my design for a cufflink according to the invention;

FIG. 6 shows a side view of the alternate embodiment, with the opposite side view being identical;

FIG. 7 shows a front view of the alternate embodiment, with the rear view being identical;

FIG. 8 shows a bottom view of the alternate embodiment, with the top view being identical; and,

FIG. 9 shows a side view of my design for a cufflink in a bended position and in use in a cuff of a shirt.

It being understood that the broken lines are for illustrative purposes only.
